US0D1006210S

(12) **United States Design Patent** (10) **Patent No.:** **US D1,006,210 S**
(45) **Date of Patent:** **** Nov. 28, 2023**

(54) **EAR IRRIGATION DEVICE**

(71) Applicant: **Shenzhen Gaodi Digital Co., Ltd.**,
Shenzhen (CN)

(72) Inventor: **Ronghua Xiao**, Shenzhen (CN)

(73) Assignee: **Shenzhen Gaodi Digital Co., Ltd.**,
Shenzhen (CN)

(**) Term: **15 Years**

(21) Appl. No.: **29/878,897**

(22) Filed: **Jun. 29, 2023**

(51) **LOC (14) Cl.** **24-01**

(52) **U.S. Cl.**

USPC **D24/108**

(57) **CLAIM**

The ornamental design for an ear irrigation device, as shown and described.

DESCRIPTION

FIG. 1 is a front and top perspective view of the ear irrigation device, showing my new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view thereof, shown in an alternative position; and,

FIG. 10 is another perspective view thereof, shown in a state of use.

The broken lines in the figures illustrate portions of the ear irrigation device that form no part of the claimed design. The broken lines showing of a cap in FIG. 10 depict environmental structure that form no part of the claimed design.

1 Claim, 10 Drawing Sheets
